TABLE LAMP

Charles Clemens, Nashville, Tenn., assignor to
Aladdin Industries, Incorporated, Nashville,
Tenn., a corporation of Illinois

Application January 4, 1954, Serial No. 28,328

Term of patent 3½ years

(Cl. D48—20)

To all whom it may concern:

Be it known that I, Charles Clemens, a citizen of the United States, residing at Nashville, county of Davidson, and State of Tennessee, have invented a new, original, and ornamental Design for a Table Lamp, of which the following is a specification, reference being had to the accompanying drawing, forming part thereof, in which:

Figure 1 is a perspective view of a table lamp showing my new design, and

Figure 2 is a cross sectional view taken on the line 2—2 of Fig. 1.

The dominant features of my design are shown in solid lines.

I claim:

The ornamental design for a table lamp, as shown and described.
